UNITED STATES PATENT OFFICE.

W. HORACE SOPER, OF BALTIMORE, MARYLAND.

CARD OR TICKET HOLDER.

SPECIFICATION forming part of Letters Patent No. 274,400, dated March 20, 1883.

Application filed May 2, 1882. (No model.)

To all whom it may concern:

Be it known that I, W. HORACE SOPER, of Baltimore city, State of Maryland, have invented certain new and useful Improvements 5 in Card or Ticket Holders; and I hereby declare the same to be fully, clearly, and exactly described as follows, reference being had to the accompanying drawings, in which—

Figure 1 is a perspective view of the device. 10 Fig. 2 is a sectional view of the same on the line xx of Fig. 3, and Fig. 3 is a top plan of the device.

The object of my invention is to furnish a 15 box or holder adapted to contain a number of cards or tickets, and provided with simple mechanism whereby a single card can be projected to a distance, permitting its ready removal from the box.

While my invention is shown in the accompanying drawings embodied in a case for 20 street-car-railway tickets, and is particularly adapted thereto, it is by no means limited in its application, as the device, modified as to size and in other obvious particulars, may be 25 used as a holder for railway-tickets at selling-stations, or for a pocket-case for business or visiting cards.

In the drawings, A is a box open at one end and having a head, B, at the other, between 30 which head and the lid of the box is a slot, b, of a width and length to permit the passage of the card or ticket. Slots a a are formed in the lid, and a strip, c, of metal of substantially the same thickness as the card or ticket, 35 passes across the bar between the slots and up through them, and is soldered to a roughened thumb-plate, C.

D is a box open at the top and at one end, adapted to slide in at the open end of the box 40 A, and having by preference a punched-up knob adapted to engage with a similar depression, f, in the box A when slipped into place. Lugs e are soldered to the inside walls of the box D, serving to hold the tickets or cards at a certain distance from the end of the box sufficient 45 to permit the strip c to pass behind the uppermost ticket when retracted. A false bottom, d, slightly curved upward at the ends, as shown in Fig. 2, so as to bear upon the ends of the 50 tickets, is mounted on a cone spiral spring, E, in the box D. It is slotted to embrace the

lugs e, whereby endwise movement of the bottom is prevented.

In operation the tickets are laid on the bottom d, and the latter being depressed, the box 55 D is slid into the box A, as shown. On sliding back the plate C the strip c passes behind the pile of tickets, and, as above stated, is of a thickness to engage only with the uppermost ticket, which is pressed closely at the ends 60 against the lid of the box A. On sliding the plate C forward the strip c catches against the end of the uppermost ticket and pushes it out at the slot b, as shown in Fig. 1, when it may be drawn completely out of the box. 65

A special advantage of my invention lies in the construction of the lugs e and false bottom d. The lugs serve as a guide for the false bottom, and prevent lateral motion thereof, while serving as stops for the tickets, as before stated, while the rear portion of the false bottom is extended beyond the slots and lugs for the purpose of preventing the strip c from engaging with the rear edge of the false bottom. Were this not so, when the last ticket 75 had been removed and the slide moved back, carrying the strip behind the lugs, (in position to engage a ticket,) it would catch behind the rear edge of the false bottom in the same manner that it engages the rear edge of a ticket, 80 and the slide being pressed forward, the false bottom would be bent or broken, or the slide or spring be broken or injured. These difficulties are all obviated by my device, which may be very cheaply constructed, occupies but 85 little space in the pocket, and is so simply and conveniently operated as to permit a ticket to be extracted with one hand and without removing the box from the pocket.

Having thus described my invention, what I 90 claim as new, and desire to secure by Letters Patent, is—

The box A, having sliding strip c, in combination with box D, having lugs e, and the spring-supported false bottom, slotted to engage with and extending to the rear of said lugs, as described, and for the purposes set forth. 95

W. HORACE SOPER.
